UNITED STATES PATENT OFFICE.

WILLIAM C. KING, OF PITTSBURG, PENNSYLVANIA.

DESIGN FOR A JUG.

SPECIFICATION forming part of **Design No. 20,505**, dated **February 3, 1891**.

Application filed December 20, 1890. Serial No. 375,348. Term of patent $3\frac{1}{2}$ years.

To all whom it may concern.

Be it known that I, WILLIAM C. KING, a citizen of the United States, residing at Pittsburgh, in the county of Allegheny and State of Pennsylvania, have invented or discovered a certain new and original Design for Jugs, of which the following is a specification.

The invention described herein relates to a new and original design for the surface ornamentation of jugs, and its characteristic feature is a series of convex ribs extending spirally from the body of the jug up and around its neck.

In the accompanying drawings, forming a part of this specification, Figure 1 is a view in elevation of a jug having my design applied thereto; and Fig. 2 is a sectional view, the plane of section being indicated by line *x x*, Fig. 1.

The ornamentation consists of a series of 20 ribs 1, their outer surface being convex. These ribs originate at or near the shoulder of the jug and extend spirally up and around the upper portion of the jug and the neck thereof, the ribs tapering or diminishing in transverse section as they extend up. The lower or larger ends of the ribs have recesses or sockets 2.

I claim herein—

The design for the surface ornamentation of jugs, substantially as shown and described. 30

In testimony whereof I have hereunto set my hand.

WILLIAM C. KING.
